Application March 18, 1955, Serial No. 495,167

5 Claims. (Cl. 273—152.1)

This invention relates to playing cards having conventional suit and denominational designations. More specifically this invention contemplates novel playing cards having conventional suit and denominational designations which may be individually observed when in stacked relationship.

It is an object of this invention to avoid the necessity of fanning or spreading a plurality of playing cards in order to observe the suit and denominational designations of the cards.

A feature of this invention is the provision of round apertured cards which are similar from the back or in other words which have the apertures similarly disposed.

Another feature of this invention is the provision of means for readily allowing the removal of any one of a plurality of stacked playing cards without disturbing the rest of the cards in the stack.

Still another feature of this invention is the provision of playing cards, the positions of which may be interchanged in a stack without removal therefrom and the designations remaining readily viewable.

For further comprehension of this invention and objects and features thereof, reference is made to the following description and accompanying drawings wherein:

Fig. 1 is a front view of a playing card of the present invention;

Fig. 2 is the front view of a stack of thirteen playing cards of the present invention; and

Fig. 3 is a sectional view through line 3—3 in Fig. 2.

Referring to Fig. 1 the circular card 1 is one card of a deck of cards having conventional suit and denominational designations. The principles of the present invention, however, are not restricted to the use of conventional suit and denominational designations as they are applicable to any type of designations. The card designations appear in a circular central section 14 and in two segments 15 and 16 which are contiguous with the section 14. The designations need not appear in section 14. In fact section 14 may have at the center thereof, a round hole for supporting the card 1. The section 14 is essentially separated from an outer tab section 17 by the apertures 18 through 23. The apertures 18 through 23 are separated from each other by the ribs 24 and by the designation segments 15 and 16. The ribs 24 are utilized to strengthen the card and any number thereof from 0 to 22 may be utilized. In the illustrative embodiment of the present invention, as shown in Fig. 1, four ribs 24 are utilized to strengthen the card 1 by connecting the sections 14 and 17. If 22 ribs 24 were utilized they would appear at approximately 14.62-degree intervals, dividing card 1 in 26 sectors including the two designation segments 15 and 16. The outer section 17 is also divided in 26 parts having 24 tabs 25 and tabs 26 and 27. The ribs 24 are each located along a diameter of the card which separates two of the tabs 25. The tabs 25 are all the same size and are somewhat smaller than the tabs 26 and 27. The large tabs 26 and 27 are opposite

2

the segments 15 and 16, respectively, and are utilized, as is hereinafter described, to remove the card 1 from a stack of similarly constructed cards.

With the card 1 divided into 26 equal sectors, as described above, a maximum of 13 playing cards may be viewed when in stacked relationship. The card 1 is not restricted to such a construction but may be designed for viewing any number of cards. For example, if only 5 cards need to be viewed the card is divided into 10 sectors. The smaller the number of sectors the larger would be the segments 15 and 16 and the larger the designations thereon. Since the maximum diameter of card 1 is generally restricted to allow for easy holding, it is not advisable to design the card 1 for viewing more cards than is necessary.

This invention is, of course, not restricted to any particular size of the card 1 or even to the relative dimensions from the outer periphery to the center of the card. Moreover the tabs 25 are unnecessary and the card 1 may simply be arcuate shaped between tabs 26 and 27. The tabs 26 and 27 need not even be arcuate shaped as illustrated. Any shaped protrusion opposite the segments 15 and 16 is sufficient.

The card 1 is shown together with 12 other cards 2 through 13 in Fig. 2 as they would appear to the viewer. Card 1, which is the two of diamonds is the top card. The other cards 2—13 from top to bottom, are respectively as follows: four of diamonds; six of diamonds; jack of diamonds; king of diamonds; ace of diamonds; ten of clubs; ace of clubs; three of hearts; nine of hearts; queen of hearts; five of spades; and eight of spades.

The large tabs 26 and 27 of cards 1—13 are staggered, each opposite the respective designation segments 15 and 16 of the cards 1—13 and with no-one being on top or covering another. For example, the large tab 26 of card 2, the four of diamonds, is opposite the segment 15 of card 2 and protrudes from beneath the tab 25 of card 1, and the tab 26 of card 3, the six of diamonds, protrudes from beneath the tabs 25 of cards 1 and 2, etc. At each of the 26 sectors of the stack one tab 26 protrudes. To arrange the cards so that the designations of all 13 cards 1—13 are readily viewable, the tabs 26 are staggered in the manner described above; one at each sector.

The edge of the tabs 26 may be colored red or black in accordance with the suit designation. Cards 7, 8, 12, and 13, the clubs and spades, have black tabs 26 and 27 as indicated in Fig. 2 and the rest of the cards have red tabs 26 and 27. The colored tabs 26 and 27 make for a rapid approximate identification of the position of the card to be withdrawn from the stack.

The tabs 26 and 27 of cards 1—13 provide for withdrawing any one of cards 1—13 from the stack. For example, if card 3, the six of diamonds, is to be removed from the stack, the tab 26, adjacent the designation segment 15, upon which the six of diamonds designation appears may be grasped to withdraw card 3. The tabs 26 and 27 are therefore utilized to arrange the cards 1—13 so that all may be viewed when they are in a stack and also to remove any one of the cards 1—13 from the stack without disturbing the others.

The tabs 26 and 27 are also utilized to change the positions of the cards. For example, if the positions of the four of diamonds and the six of diamonds are to be interchanged, card 3, the six of diamonds, is rotated one sector counterclockwise and card 2, the four of diamonds, is rotated one sector clockwise. The tabs 26 and 27 are utilized to rotate the cards 2 and 3. Any two of the cards 1—13 may in this manner have their positions interchanged without removing either from the stack merely by rotating them. The cards to be interchanged, more-

over, need not be adjacent to each other in the stack. In conventional rectangular cards, the cards must be removed from the fanned stack to be interchanged.

Any two of the cards 1-13 may be interchanged in this manner because they may all be viewed, whatever their respective positions from the front of the stack to the back, as long as the segments 15 or tabs 26 of two or more cards do not coincide. If the cards 1-13 have a round hole, not shown, at the center of section 14, they may be supported by a peg inserted therethrough and readily rotated.

The embodiment described above is merely illustrative. Various modifications are possible without departing from the spirit and scope of the principles of this invention. For example, as described above, the maximum number of cards that may be viewed in a stack without fanning them out may be varied. The apertures 18 through 23, moreover, may be transparent material instead of apertures, or the entire card may be covered with a transparent sheet on one or both sides. The cards 1-13 do not have to be bi-symmetrical. For tri-symmetry, for example, with the maximum number of cards to be viewed in a stack being seven, there are three designation areas, with the card being divided into 21 sectors instead of 14. The card can have four designation areas, or be divided into 28 sectors, etc. The designations of each card would then be viewable in three, four or more places, respectively. The card, moreover may be shaped as a polygon instead of a circle, and the apertures 18-23 may similarly be polygonally shaped.

What I claim is:

1. A deck of round playing cards, with each of said round playing cards having a circular central area, two designation areas bordering said central area at opposite sides thereof, a circular peripheral area contiguous with said designation areas and forming with said central area symmetrical arcuate apertures between said designation areas to allow for the simultaneous viewing of said designation areas of other of said cards when held in stacked relationship.

2. A deck of round playing cards with each of said playing cards having a circular central area, two desig-

nation areas contiguous with said central area and located at opposite sides thereof, a circular peripheral area contiguous with said designation areas and forming with said central area two arcuate slots between said designation areas, the length of each of said slots being a predetermined integer multiple of the width of said designation areas, and a tab contiguous with said peripheral area adjacent each of said designation areas.

3. Circular playing cards divided into a number of sectors equal to twice the maximum number of said cards that are required to be simultaneously viewed in a stack, each of said cards having a designation area in two of said sectors at opposite sides of said cards, an aperture in each of the rest of said sectors, strengthening ribs between some of said apertures, a peripheral tab in each sector, said tabs that are in the designation area sectors being larger than the rest of said tabs.

4. Circular playing cards in accordance with claim 3 wherein said larger tabs are colored in accordance with the suit designations of the cards.

5. A deck of circular playing cards having conventional denomination and suit designations, each of said cards having a plurality of peripheral tabs, a circular strip area including suit and denomination designation sections positioned respectively adjacent said peripheral tabs, and transparent sections for viewing said designation sections of others of said cards, each of said transparent sections having a radial width equal to the radial width of each of said designation sections and an arcuate length which is a predetermined integer multiple of the length of each of said designation sections.
